DES. 2188

Henry S. Hubbell and Alfred S. Hubbell, of Buffalo, N.Y.

Letters Patent No. 2188 Dated, Oct. 10-1865.

Design for a Parlor Stove.

The schedule referred to in these Letters Patent and making part of the same.

To all whom it may concern.

Be it known that we, Henry S. Hubbell and Alfred S. Hubbell, of the City of Buffalo, County of Erie and State of New York, have invented or produced a new and original design for a Parlor Heating Stove called the "Caloric" and we hereby declare that the following is a full and exact description of the same, reference being had to the accompanying photograph and letters of reference marked thereon.

The photograph represents the back end and front door of stove.

Letter A is the back end.

Letter B is the front door.

What we claim as our invention and desire to secure by Letters Patent is,

The ornamental design for back end of stove marked A, and the ornamental design for the front door marked B, in the accompanying photograph.

Witness,

James H. Kirby
Alfred S. Hubbell.

{ Henry S. Hubbell.
Alfred S. Hubbell.
